SPOON OR SIMILAR ARTICLE OF FLATWARE

Marion Weeber, New York, N. Y., assignor to National Silver Company, New York, N. Y., a corporation of New York

Application May 24, 1950, Serial No. 10,134

Term of patent 14 years

(Cl. D54—12)

To all whom it may concern:

Be it known that I, Marion Weeber, a citizen of the United States, city, county, and State of New York, have invented a new, original, and ornamental Design for a Spoon or Similar Article of Flatware, of which the following is a specification, reference being had to the accompanying drawing, forming a part hereof, in which:

Fig. 1 is a front elevational view of a spoon embodying my new design.

Fig. 2 is a rear elevational view thereof.

Fig. 3 is a sectional view taken on line 3—3 of Fig. 1.

The essential features of my design reside in the parts shown in full lines.

I claim:

The ornamental design for a spoon or similar article of flatware, as shown and described.

MARION WEEBER.
